UNITED STATES PATENT OFFICE.

ANDREW I. GOVE, OF SAN FRANCISCO, CALIFORNIA.

IMPROVED WRENCH.

Specification forming part of Letters Patent No. **28,665**, dated June 12, 1860.

To all whom it may concern:

Be it known that I, ANDREW I. GOVE, of the city and county of San Francisco, and State of California, have invented a new and Improved Wrench, which I call "Gove's Self-Adjusting Wrench;" and I do hereby declare that the following is a full, clear, and exact description of the construction and operation of the same, reference being had to the annexed drawings, making a part of this specification, in which—

Figure 1 represents the wrench as complete. Fig. 2 is a sectional view. Fig. 3 represents the stationary jaw and shaft. Fig. 4 represents the movable jaw with the rack, &c. Fig. 5 is a plate, the use of which can be better explained hereinafter.

A represents the stationary jaw of a wrench with a shaft or arm *a*, the heel of which is round, as shown at *b*, terminating with a screw *c*.

B is the movable jaw sliding on the shaft or arm *a* of the stationary jaw, having attached to each side arms *d d'*, upon which are racks *e e'*.

D is a hollow handle, of wood or metal, through which is passed the shaft or arm *a* of the stationary jaw, and confined thereto by the nut *E*; also, in same hollow is passed the rack of the movable jaw *B*, the arms *d* working on each side of the shaft *a*.

S is a spiral spring coiled around the heel of the shaft *a*. *h* (seen more particularly in Fig. 5) is an oblong plate sliding on the heel *b*, pressing against the rack *e e'*.

F is a lever attached to the handle *D*, as shown at *G*.

H is a spring.

K is a pin passed through a shoulder on the lever *F*.

P is a catch to hold lever *F*.

Operation: When the lever *F* is let loose from the catch *P* it is thrown by the spring *H* into position, as shown by the dotted lines in Fig. 2, and the pin *K* being released from the rack *e e'* the movable jaw *B* is pressed against the stationary jaw *A* by means of the spiral spring *S*, the plate *h* being pressed against the ends of the arms *d d'*. To use the wrench, draw back the arm *B* to the necessary distance, press upon the lever *F* by the grip of the hand, which will throw the pin *K* into the rack *e e'*, and hold the jaw firm upon the nut or bolt. To change the position of the wrench upon the nut or bolt, it is not necessary to move it therefrom, but simply release the grip of the hand. The lever *F* will rise, releasing the pin *K* from the rack, thus allowing the jaw *B* to yield in passing the wrench around the nut or bolt. When brought into proper position, grasp the handle firmly, so that the pin *K* will be thrown into the rack again, and so on till the work is completed.

Having thus fully described the nature and object of my invention, what I claim therein as new, and desire to secure by Letters Patent, is—

1. In combination with the rack or racks on the shank of the movable jaw, the lever and pin or stop connected to the handle for the purpose of holding and releasing the movable jaw, substantially as described.

2. In combination with the rack on the movable jaw and the stop and lever on the handle, the coiled spring *S* for throwing out the movable jaw when the lever is compressed or the stop raised out of the rack, substantially as described.

ANDREW I. GOVE.
